[57] CLAIM

The ornamental design for a watertight container for small personal articles, as shown and described.

DESCRIPTION

FIG. 1 is a top perspective view of a watertight container for small personal articles, showing my new design;

FIG. 2 is a bottom perspective view thereof;

FIG. 3 is a top perspective view thereof with the cover removed;

FIG. 4 is a bottom perspective view of the cover;

FIG. 5 is a reduced scale cross-sectional view taken on line 5—5 of FIG. 7;

FIG. 6 is a bottom plan view of FIG. 7;

FIG. 7 is a front elevational view; and

FIG. 8 is a top plan view thereof.

FIG. 1

FIG. 2

FIG. 4

FIG. 3
